UNITED STATES PATENT OFFICE.

CHARLES N. JACKSON, OF NEW YORK, N. Y.

FILING AND POSTING SYSTEM.

Substitute for application Serial No. 328,657, filed October 6, 1919. This application filed February 27, 1922. Serial No. 539,751.

My present invention relates to filing systems and to combined ledger and statement posting.

The objects of the invention are to provide a simple and practical visible filing system in which the record sheets will be readily accessible and can be easily removed and replaced.

The invention is particularly suited to a loose-leaf ledger system and in this connection it is one of the objects of my invention to provide for the simultaneous posting of both the ledger and the statement sheets.

Briefly, the invention comprises in part a series of sequentially arranged carrier elements of graduated size and arranged to support the ledger or other record sheets with the upper edges visible one behind the other. In the case of a ledger posting system these carrier elements are also constructed to support the statement sheets beneath the ledger sheets and with an interposed transfer surface for effecting the transfer of the impression from the ledger sheet to the statement sheet.

Various other features of the invention will appear as the specification proceeds and will be made clear by reference to the accompanying drawing wherein I have illustrated the invention embodied in different, practical forms.

In said drawing, Figure 1 is a perspective view of a portion of a visible filing ledger and statement posting system.

Figure 2 is a perspective view of one of the carrier cards or elements showing the ledger, statement and carbon sheets in position thereon.

Figure 3 is a horizontal sectional view taken on substantially the line 3—3 of Figure 2.

Figures 4 and 5 are broken detail views of two of the sequentially disposed carriers.

Figure 6 is a detail perspective view on a smaller scale of a slightly modified form of carrier and ledger construction.

In the illustration the carriers are designated 5. The size of these cards depends upon the character of the record which is to be carried thereby. In the case of a ledger and statement posting system, such as illustrated, the carrier card will be substantially the dimensions of the ledger sheet. This ledger sheet is designated 6 and is indicated

in the first form of the invention shown as made of a separate sheet, having a folded upper edge 7 engaged over the upper edge of the carrier and detachably secured thereto by means of an integral tongue 8 which is slipped through a slit or slot 9 formed in the upper portion of the carrier. These ledger sheets are preferably ruled and provided with the necessary indicia for keeping the records intended.

The transfer surface is provided in the instance illustrated, by a sheet 10 of carbon paper secured along its upper edge at 11 to the upper portion of the carrier.

12 designates the statement sheet which is supported on the face of the carrier beneath the transfer surface and in position to receive the impression from the ledger sheet. This statement sheet is adjustably held in position by means consisting in the present disclosure of a pair of oppositely disposed laterally projecting fingers 13 on the carrier near the opposite lower edges thereof and a vertically projecting holding finger 14 disposed in a plane between the laterally projecting fingers.

In practice the statement sheet is folded on a line to bring the top portion thereof into register with the last entry on the ledger sheet and the statement is applied to the face of the carrier with the laterally projecting tongues 13 entered between the folds of the statement and the upwardly projecting tongue 14 engaging over the lower folded edge of the statement. In this position of the parts the statement is held from dropping downward by the tongue 14 and is held against shifting upwardly or sideways by the laterally projecting fingers 13, which as indicated, are engaged in the right of the fold.

Where the entry on the statement sheet is to be made near the bottom of that sheet, the sheet may be supported from the top instead of at the bottom, as in the instance first described. For this purpose I have shown the carrier as provided with a second set of the holding fingers adjacent the upper edge thereof, the same being designated 13^A and 14^A respectively and being used in the same way as described, except that in this instance, the fold being at the top of the statement and being hooked over the laterally projecting fingers 13^A, said fingers will hold the statement against downward and 110

lateral movement and the downwardly projecting finger 14^A, engaging over the upper folded edge of the statement, will hold the same against upward shifting movement.

From the description thus far, it will be seen that the carrier supports the ledger and statement sheets with the interposed transfer surface in proper relation to cause an entry made on the ledger to be simultaneously impressed in proper position upon the statement sheet. The statement sheet is, by the means described, readily adjusted and supported in proper position on the carrier to receive such impression and both the statement and the ledger sheets are easily removable from the carrier.

As a possible modification the ledger and carrier may be made integral or be permanently connected as indicated in Figure 6. In this view, I have shown the ledger and carrier sheets combined in one, the same consisting of the front and back sheets 15 and 16 connected together at the top by a folded edge 17 and provided each with the integral holding fingers 13, 14, 13^A and 14^A previously described. In using this form of the device the front sheet, or page 15 serves as the ledger sheet and the back sheet 16 serves as the carrier, the statement being engaged on the carrier in the manner before described and the transfer surface being interposed between the back of the front sheet and the statement. In this case the transfer sheet may be lightly pasted at its upper edge to the face of the sheet then serving as the carrier. After the front sheet 15 has served its purpose as a ledger page the sheets may be reversed so as to bring the sheet 16 to the front and the sheet 15 at the back to serve as a carrier. Consequently, the folded sheets, in this connection, serve alternately as carrier and ledger pages.

In Figure 1 I have shown how the carriers may be made of graduated height to form a visible filing system. In the instance illustrated there are ten carriers to a set, graduated in height and arranged one behind the other so as to each expose the upper edge of the record sheet supported thereby. In the illustration I have shown only three of these sets, but it will be obvious that these may be multiplied to the extent required.

The visible feature just described enables one to quickly locate a desired record sheet since all the record sheets of each set are exposed and it is possible by glancing at the last sheet of each set to quickly determine in which set the desired record is located.

The ledger or record sheets which are applied to the carriers of graduated height are preferably each of the same height so that they may be readily interchanged on different carriers. This provides for the expansion or contraction of the system to meet different requirements. In practice, the carriers may

be left blank at different points so as to provide for the insertion of new record sheets. Where conditions warrant, a whole new set of carriers may be interposed between the adjacent sets of filled carriers to take care of the growth of the system.

From the foregoing it will be apparent that the visible filing feature is particularly valuable for the filing of records in quickly accessible relation and furthermore, that this feature is of particular value in connection with the automatic simultaneous posting of the ledger and statement sheets since it enables the proper sheets being located without delay and without fingering or wearing the other ledger sheets.

The various sheets are preferably made so that they will readily pass through a typewriting machine and in the construction disclosed it will be seen that the holding fingers are all covered so as not to interfere with the proper passage through the typewriter.

In Figures 4 and 5 I have shown how the holding fingers on the different carriers are graduated or placed at different levels in accordance with the height of the carrier to properly hold the statements. Usually these fingers are disposed the same distance from the top of the carrier irrespective of the total height of the carrier, such distance substantially corresponding to the length of the ledger page, as indicated in Figure 1. This construction causes the ledger and statement sheets to fit the carriers irrespective of the total height thereof. In other words, the ledger sheets and statements are all interchangeable on different carriers.

What I claim is:

1. In a visible filing system, sequentially arranged supporting cards of graduated and successively greater height, and information sheets of uniform height interchangeably engageable on said cards of different height and having folded upper edges engaged over the upper edges of the cards and thereby supported by said cards at graduated heights and with their front faces visible one behind the other, said sheets and supporting cards having means engaging at the rearward folds of the information sheets for detachably securing said sheets on the cards.

2. In a visible filing system, a plurality of sets of supporting cards each set comprising a series of sequentially arranged cards of successively greater heights, and information sheets of substantially uniform height supported on and interchangeably engageable with any of said supporting cards, said supporting cards having substantially straight upper supporting edges and the information sheets being folded and having their folded edges engaged over and resting directly on said upper supporting edges.

of the cards, said information sheets bearing indexing data on their forward faces adjacent the folds forming the upper edges of the sheets and arranged all in each set 5 to be visible one behind the other at the tops of the sheets.

3. In a visible filing system, sequentially arranged supporting cards of graduated and successively greater heights, and information sheets of substantially uniform height 10 detachably and interchangeably engaged over the upper edges of said supporting cards, said information sheets bearing indexing data on their forward faces adjacent the upper edges thereof, visible at the tops of the sheets, one behind the other, when the sheets are thus engaged on the supporting cards.

4. In a visible filing system, sequentially arranged supporting cards of graduated height, information sheets supported on said cards with their upper edge portions visible one behind the other and means for adjustably supporting other sheets on the cards beneath said information sheets.

5. In a visible filing system, sequentially arranged supporting cards of graduated height, information sheets supported on said cards with their upper edge portions visible one behind the other and means for adjustably supporting other sheets on the cards beneath the first sheets and transfer surfaces interposed between said sheets on the cards.

35 6. In a visible filing system, sequentially arranged supporting cards of graduated height, information sheets supported on said cards with their upper edge portions visible one behind the other and means for adjustably supporting other sheets on the cards beneath the first sheets and transfer sheets supported on the cards between said first mentioned sheets.

7. In combination, carrier cards of graduated height provided each with means for supporting a sheet on the face thereof and for supporting a second sheet at the upper edge thereof overlying said first sheet and transfer sheets supported by said graduated carrier cards in position to stand between the sheets first mentioned.

8. In combination, carrier cards of graduated height provided each with means for supporting a sheet on the face thereof and for supporting a second sheet at the upper edge thereof, sheets supported on the faces of said cards, sheets supported at the upper edges of the cards overlying the first sheets and visible one behind the other, and transfer sheets on the cards between the first mentioned sheets.

9. In combination, carrier cards of graduated height provided each with means for supporting a sheet on the face thereof and for supporting a second sheet at the upper

edge thereof, sheets supported on the faces of said cards, sheets having folded edges engaged over the upper edges of the cards with their front portions visible one behind the other, and transfer surfaces interposed 70 between said sheets.

10. In combination, carriers having supporting and positioning tongues at the upper and at the lower portions thereof, sheets engageable with either said upper or said lower tongues and overlying sheets engageable on the carriers over said first sheets.

11. In combination, carriers having supporting and positioning tongues at the upper and at the lower portions thereof, sheets 80 engageable with either said upper or said lower tongues, overlying sheets engageable on the carriers over said first sheets and transfer sheets on the carriers between said 85 first mentioned sheets.

12. In combination, carriers having supporting and positioning tongues at the upper and at the lower portions thereof, sheets engageable with either said upper or said lower tongues and overlying sheets having 90 folded upper edges, engaged over the upper edges of the carriers.

13. In combination, carriers having supporting and positioning tongues at the upper and at the lower portions thereof, sheets 95 engageable with either said upper or said lower tongues, overlying sheets engageable on the carriers over said first sheets and said carriers being of graduated heights to thereby expose a portion of said overlying sheets 100 one behind the other.

14. In combination, carriers having supporting and positioning tongues at the upper and at the lower portions thereof, sheets engageable with either said upper or said lower tongues, overlying sheets engageable on the carriers over said first sheets and said carriers further having slits near their upper edges and the overlying sheets having tongues engageable in said slits. 110

15. In combination, a carrier having a laterally projecting tongue and a vertically projecting tongue at one side of said laterally projecting tongue and a folded sheet on the carrier with its folded edge engaged by the vertically projecting tongue and with the laterally projecting tongue engaged between the folds of the sheet. 115

16. In combination, a carrier having spaced oppositely projecting tongues, a third tongue disposed in a plane between the first tongues and projecting at an angle thereto and a folded sheet on the carrier having the oppositely projecting tongues engaged between the folds thereof and the third tongue overlying the folded edge 120 thereof. 125

17. A carrier having laterally projecting tongues at the upper and lower portions thereof, vertically projecting tongues on a 130

line between the ends of said laterally projecting tongues and a sheet having a folded edge engageable beneath one of the vertically projecting tongues and adapted to receive the corresponding laterally projecting tongues between the folds thereof.

18. In combination, a carrier having spaced oppositely projecting tongues, a third tongue disposed on a line between the first tongues and projecting at an angle thereto and a second set of similar tongues disposed below the set first described and the intermediate tongues of the two sets being substantially oppositely disposed and projecting in opposite directions.

19. In combination, a carrier having spaced oppositely projecting tongues, a third tongue disposed on a line between the first tongues and projecting at an angle thereto and a sheet secured at the upper edge of said carrier and overlying the face of the same.

20. A carrier having pairs of laterally projecting tongues at the upper and lower portions thereof, vertically projecting tongues on lines between the ends of said pairs of laterally projecting tongues and a front sheet attached at its upper edge to the upper edge of the carrier and overlying the face of the same.

21. In combination, a plurality of carriers having spaced oppositely projecting tongues and a third tongue disposed on a line between the first tongues, projecting at an angle thereto and said carriers being of graduated height and disposed in a set one behind the other.

22. In combination, a plurality of carriers having spaced oppositely projecting tongues

and a third tongue disposed on a line between the first tongues, projecting at an angle thereto and said carriers being arranged in a plurality of sets, each set consisting of carriers of graduated height, disposed one behind the other.

23. A plurality of carriers having pairs of laterally projecting tongues at the upper and lower portions thereof, vertically projecting tongues on lines between the ends of said pairs of laterally projecting tongues, and said carriers being of graduated height and disposed in a set one behind the other.

24. A plurality of carriers having pairs of laterally projecting tongues at the upper and lower portions thereof, vertically projecting tongues on lines between the ends of said pairs of laterally projecting tongues, and said carriers being arranged in a plurality of sets, each set consisting of carriers of graduated height disposed one behind the other.

25. In combination with carriers of graduated height, ledger sheets of equal height interchangeably engageable with different carriers, statement sheets of equal length and holding means for said statements arranged on the carriers at different heights and therefore securing the statements at different levels.

26. In combination, a carrier having means for securing a statement sheet on the face of the same and a ledger sheet hingedly secured along its upper edge to the upper edge of the carrier.

In witness whereof, I have hereunto set my hand this 23rd day of February, 1922.

CHARLES N. JACKSON.
